HEAT COIL OPERATED THERMAL SWITCH

Robert Hetherington, Sharon Hill, Pa., assignor
to Robert Hetherington & Son, Inc., Wilming-
ton, Del., a corporation of Delaware

Application October 17, 1942, Serial No. 462,350

17 Claims. (Cl. 200—122)

My invention relates to snap switches of the type in which a bimetallic body is pushed past the center to throw the switch and is returned in part by reason of heat developed in a circuit shunted across from the main circuit when the main circuit is closed.

One of the purposes of the invention is to use a clicker switch in the thermally effected opening of a switch, forming with it a bimetallic pair and heat operating the bimetallic pair either by a mere overload to the pair or a sudden short circuit through the bimetallic pair, to generate the effective heat directly into the pair or by heating the pair by increasing the temperature surrounding the pair.

A further purpose is to interpose a time element into the operation of a plunger-operated switch, so that the switch will be retracted after expiration of the time interval. The range of time interval is within the control of the designer but within the designed range is capable of adjustment by altering the strength of reverse pressure against the clicker disc when thrown.

A further purpose is to shunt a heater circuit to ground through a clicker switch when the clicker switch has been thrown.

A further purpose is to provide a heater coil shunted across part of the circuit, whereby the temperature within the switch is raised to a predetermined point where a bimetallic clicker disc will be operated.

A further purpose is to provide a bimetallic clicker switch which can be thrown past its critical position by a plunger and will stay in that position except as thermally operated, preferably making adjustable the pressure opposing that throw and, therefore, the time before resetting.

A further purpose is to provide a bimetallic clicker disc and contacts thrown by it, the disc being capable of being thrown beyond its critical position and staying there except as thermally reset and in connection with this to assist the resetting by a spring which is adjustable to vary the resetting urge of the spring.

Further purposes will appear in the specifications and in the claims.

Figure 1 is a central longitudinal section of the preferred form of my switch in its normally open position.

Figure 1^a is a fragmentary section corresponding to Figure 1 but with the parts in closed position.

Figure 2 is a section of Figure 1 taken upon line 2—2.

Figure 3 is a fragmentary elevation of the bimetallic disc and its contact arms.

The switch is encased within a cylindrical metallic shell 8, open at the rear end. The front end of the shell is reduced in diameter at 7, forming an internal flange 8. Externally the shell presents a threaded boss 9 which can be mounted within a threaded opening in any suitable grounded board, or mount, not shown.

The internally flanged shell is counterbored at 10 and apertured to form a shoulder 11 and cylindrical internal guide wall 12.

Within the guide wall 12 slides an operating button 13 in plunger form whose flange 14 engages shoulder 11. The casing and plunger are electrically conducting and are grounded. The plunger is rearwardly bored at 15 to receive a plug 16 which screws into the bore 15 or is roughened to add to its frictional engagement within that bore.

The plug is through-bored at the front at 17 and counterbored from the front rearwardly at 18, producing an internal forwardly-facing shoulder 19.

Within the bore lies a bolt 21 which passes through the center of the disc of a bimetallic clicker 22, which operates effectively as a spring because of its radial compression of the material up to a certain point after which the radial expansion snaps it over. The clicker 22 is therefore treated herein as a clicker spring.

The head 23 of the bolt has play within the counterbore of the plug so that the disc 25 will be free to jump rearwardly by the heater coil 35 form as later explained. The nut 24 affords front abutment for the forward end 26 of a spiral spring 27.

The central disc bimetallic clicker spring 22 is shown best in Figures 1 and 3 and includes two 40 dissimilar metals bonded together, namely a disc 28 united to a central clicker disc portion 29. The clicker disc 29 is "full" at the middle so as to snap from a normal position at which it convexes toward the operating plunger, through a 45 position where its central portion is approximately in the plane of its edges, to the other side of this plane where it convexes away from the operating plunger. It is likewise capable of being snapped back to normal position (from that of 50 Figure 1^a to that of Figure 1) by being pushed back to approximately the middle so as again to snap across this plane through its edges, to initial position. This clicker form of switch is shown in my application for patent for Clicker plunger

55 switch Ser. No. 359,035, filed September 30, 1940,

issuing November 10, 1942, as Patent No. 2,301,874.

The rear part 28 of the thickness of the switch disc shown in Figure 1 is made of material which differs in its co-efficient of expansion from the co-efficient of expansion of the clicker disc part of the complete disc. If the bimetallic disc, therefore, be pushed by the operating plunger so as to snap beyond the central plane and convex the composite disc to the left in Figure 1, the disc will continue to act as a clicker disc alone unless and until there be such a change in the temperature within the casing as will cause relatively excessive expansion of the thermally responsive material. The composite diaphragm will then snap back to the initial position.

The composite diaphragm terminates at its perimeter in holding sections 30 of larger diameter than the part relied upon for clicker functions. The diaphragm carries contact-supporting arms 31 and 32.

Both the holding sections at the perimeter and the arms 31 and 32 at or near bends 33 are rigidly attached to the disc and the arms are in good electrical contact with the diaphragm.

The clicker spring is gripped directly at its perimeter between the front end section 34 of insulation within the casing or shell and the axially projecting flange 35 of the cylindrical insulation 36. The complete insulation of the body of the casing includes also a rear insulation disc 37. Within the rear disc are carried binding posts 38 and 39 and the fixed contacts 40 and 41 which are rigidly mounted upon the posts 38 and 39 and are usually welded to them.

Mounting the composite clicker body rigidly by its perimetrical extensions leaves the intermediate central part of the composite clicker body free to move and to be moved axially with respect to the plunger and with respect to the plane of the clicker disc. Its movement in a rearward direction (that is toward the left of Figure 1) is produced by pressure upon the plunger communicated directly to the disc, and is counter to the pressure of the spring through the nut.

The rear end of the spiral spring abuts against the flange of a collar 42. For centralizing purposes the spring surrounds a guide or core 43 forming part of the collar.

The collar is rigid with a bolt 44 which as disclosed is threaded within a metallic spool 45 and within the central part of insulation disc 37. Its longitudinal position along the axis of the thread can therefore be set for adjustment purposes by a screw driver inserted from the end at 47 and fitting within a screw slot as shown.

The composite clicker disc, as so far described constitutes a thermal pair of which the disc described as thermally responsive merely has a different co-efficient of heat expansion from that of the clicker disc, so selected as progressively to increase pressure from the left against the clicker switch as the temperature within the chamber increases. The disc is limited in its movement to the left in Figure 1 by engagement with the end of the coil form 45.

If the spiral spring be strong enough, obviously the clicker disc will not remain in its position at the left when "clicked," but as soon as pressure upon the plunger is removed immediately will spring back to the position of Figure 1. However, the spiral spring may be made light enough in its pressure so that the clicker disc will remain in its position in Figure 1^a as moved to the left from that shown in Figure 1. That is, the condition in the present case where it is desired to

have the clicker disc remain in closed position (Figure 1^a) until operated upon by a force additional to that of the spiral spring.

With the parts in "open" position in Figure 1, the arms 31 and 32 lie generally as seen, with their contact discs 49 and 50 out of engagement with fixed contacts 40 and 41. However, when the composite clicker disc is reversed in position from that seen in Figure 1, i. e., as in Figure 1^a, the contact discs 49 and 50 close the circuit from the binding posts through the arms and the composite clicker disc.

The present invention contemplates closing a shunt circuit 51 through a resistance coil within the casing at the same time that the main circuit is closed. The spiral spring is always tending to open the circuit. The present invention relies upon the shunt circuit to raise the temperature within the shell or casing sufficiently so that the thermal pair making up the composite disc, with the ever-present help of the spiral spring 27 will cause resetting of the composite disc to the position seen in Figure 1. The structure by which this is accomplished is as follows:

The preferably metallic spool 45 supports a shunt winding in the form of a resistance coil 51 which at one end 52 is electrically connected to the spool. The other end 53 of this winding is connected with the casing or shell.

As a result, when the main circuit is closed as seen in Figure 1^a the main circuit passes across from one fixed contact to the other fixed contact plate or strip through the contact discs 49, 41, the arms 31, 32 and the composite clicker disc, and at the same time current leaks to ground (casing or shell) from the composite disc through nut 24, spiral spring 27, collar 42, bolt 44, spool 45, resistance coil 51 and the grounded shell.

Since one side of the main circuit closed is grounded a shunt flow passes through the resistance coil at all times when the main circuit is closed. There is also, of course, a slight heating effect within the chamber due to flow of the main current through the resistance of the arms and composite disc.

In operation the plunger is pushed in, throwing the clicker to closed switch position seen in Figure 1^a. The clicker stays in this closed position until sufficient heat has been developed to cause resetting of the switch to open position, introducing a time element within the circuit and making it possible to predetermine the range of time elapsing before the switch current is interrupted, as by the type and hence "range" of clicker (composite) discs used, the number of turns, strength, etc. of the spring which presses the clicker toward opening, etc.

It is also possible to adjust the time to elapse before the interruption of the circuit (within the predetermined range) with great nicety by altering the strength of the continuing spring pressure which assists the thermally-developed opening pressure.

From Figures 1 and 1^a it will be seen that the spool 45 upon which the heat coil is mounted is centered and at the same time is rigidly mounted upon the rear disc insulation by providing a projection 54 at the rear of the spool to fit into a recess 55 in the rear disc insulation and by holding the parts upon the insulation by the screw 46. To considerable advantage this screw may be threaded into both of the adjoining parts.

The invention recognizes that much more nearly exact adjustment of the time element can be made when the heat developed is used to op-

erate a thermally responsive disc acting to throw a clicker disc and representing, as it were, the balance of control between a clicker switch thrown beyond the center and a nearly balancing spring tending to open the switch; and that the extent of heat required to open the switch, and therefore the time during which heat must be developed to secure this switch opening overbalance, is capable of very exact setting and control when the effect of the balancing means (here the spiral spring) to open the switch can be adjusted from the outside. This can be done while the switch is being tested or operated.

It will be evident also that the thermal unit is wholly out of circuit and inoperative when the clicker switch main contacts are open. The presence of the heat coil as a constant shunt across the switch, open or closed, makes it available for switch-delay purposes when the clicker switch is closed.

The heating coil is connected to its spool at one end and to grounded casing at the other end and is therefore shunted across a part of the main circuit, that is, across a part of the circuit from movable contact to movable contact through a clicker diaphragm.

When the clicker switch is open, that is, when the clicker is convex toward the right as in Figure 1, the spiral spring fits, directly or through the nut 24, into the concavity thus formed at the left, giving slack under the head of the bolt and ensuring good contact of the composite disc with the nut and through it with the spiral spring, the abutment of the spiral spring, the metallic spool and the heat coil.

It makes little difference whether the spiral spring press against the nut 24 and through it against that face of the composite disc which is presented to the left in Figure 1, or if this spring press directly against the composite disc, except that contact through the nut conveniently can be made closer to the center of the composite disc than would otherwise be the case.

When the composite disc has been plunger-thrown to the closed switch position (Figure 1^a) and pressure upon the plunger has been released, the pressure toward remaining closed, due to the convexity of the composite disc toward the left only slightly overbalances the pressure of the spiral spring toward the right tending to open the switch; and the amount of this overbalance represents the pressure which must be overcome by reason of temperature change of the thermal pair comprising the composite disc.

Stated in another way, the spiral spring and the thermal effect upon the composite disc due to the heater coil must together overcome the residual closing pressure left in the disc after the plunger has been operated and has been released, and for this reason if the spiral spring be weakened, the heater coil must take a larger proportion of this duty and therefore the switch must remain closed a longer time; while if the spiral spring be strengthened, the length of time of heater coil operation and the length of time introduced by the switch is reduced.

It will further be recognized that as set forth in my application No. 359,035 the second disc of the bimetallic pair along with the clicker disc constitutes means for resetting the clicker disc in response to heat, which resets at a continued overload, resets with great rapidity on short circuit and contributes to the resetting effect where a heater coil is used.

It will further be recognized that the heat-

operated automatic resetting of the clicker disc is available when the heat coil is used.

It will be evident that the return circuit from the disc to the heat coil conveniently passes through the spool 45.

In view of my invention and disclosure variations and modifications to meet individual whim or particular need will doubtless become evident to others skilled in the art, to obtain all or part of the benefits of my invention without copying the structure shown, and I, therefore, claim all such in so far as they fall within the reasonable spirit and scope of my invention.

Having thus described my invention what I claim as new and desire to secure by Letters Patent is:

1. A thermally opened clicker time switch comprising a casing having fixed contacts therein, a seat for a clicker disc, a bimetallic clicker disc adapted to be clicked transversely past its center and having arms adapted to engage the fixed contacts and closing or opening an operating circuit through the disc, a spring tending to resist switch closing movement of the disc, and shunt current means passing the shunt current through the spring and tending to heat the disc and thereby open the switch.

2. A thermally opened clicker time switch comprising a casing having fixed contacts therein, a seat for a clicker disc, a bimetallic clicker disc adapted to be clicked transversely past its center and having arms adapted to engage the fixed contacts and closing or opening an operating circuit through the disc, and electrically connected to the disc, a spring resisting throw of the clicker, and a shunt circuit passing through the spring and disc and effective to heat the disc.

3. In a clicker switch, a grounded casing, binding posts and fixed contacts connected therewith, a mount for a disc, a bimetallic switch clicker disc, movable contacts connected with the disc, means for throwing the clicker disc in one direction, spring means opposing the throw of the clicker disc, and shunt means passing current through the spring between the disc and the casing for heating the disc and thereby causing reversal of the position of the disc.

4. In a clicker switch, a casing, binding posts and fixed contacts connected therewith, a switch circuit including a normally forwardly convexed clicker disc forming part of a thermal pair, movable contacts connected with the disc, the thermal pair when heated tending to reverse the normal throw of the clicker disc in one direction, adjustable spring means connecting with the normally concave side of the disc, opposing the throw of the clicker disc, and a shunt circuit passing from the disc to the casing through the spring and heating the thermal pair.

5. In a clicker switch, a casing, binding posts and fixed contacts connected therewith, a switch circuit including a bimetallic clicker disc forming part of a thermal pair and movable contacts connected with the disc, the thermal pair when heated tending to reverse the normal throw of the clicker disc, means for throwing the clicker disc in one direction, a spring tending to throw the disc in the opposite direction and shunt current means passing through the spring and by increase of temperature upon the switch effective when added to the spring to reverse the disc.

6. A pair of normally open fixed circuit contacts, a snap switch having a bimetallic diaphragm, one part of which is of clicker type and

the other part forming with it a thermal pair, and arms controlled by the diaphragm, adapted to close the switch through the diaphragm with movement of the diaphragm from normally open position convex toward the front to closing position convex toward the rear, a spring tending to open the switch, a casing forming a closed chamber about the pair, a heating coil within the chamber connected through the spring as a shunt across a part of the circuit through the diaphragm, and means for operating the diaphragm whereby when the circuit is closed, current passes through the diaphragm and through the heating coil.

7. A pair of normally open fixed circuit contacts, a snap switch having a bimetallic diaphragm, one part of which is of clicker type and the other part forms with it a thermal pair, and arms controlled by the diaphragm adapted to close the switch through the diaphragm between the fixed circuit contacts with movement of the diaphragm from normally convex open position to concave closing position, a casing forming a closed chamber about the pair, a heating coil within the chamber connected as a shunt across a part of the circuit through the diaphragm, a metallic spool for the coil, through which form the shunt current passes, and means for operating the diaphragm, whereby when the circuit is closed, current passes through the diaphragm and through the heating coil.

8. A clicker switch having a clicker disc and a second disc forming a thermally responsive pair, contact closing arms closing a circuit through the switch when the clicker disc is thrown, a spiral spring opposing the throw of the clicker switch, a resistance shunted across the path of the circuit closed when the clicker is thrown, tending to operate the thermally responsive switch and to open the circuit, and thus introducing a time element, and means through part of which the shunt current passes for adjusting the pressure of the spiral spring, to alter the time element introduced by the shunt.

9. In a snap switch, a bimetallic diaphragm presenting a thermal pair, normally convexed, means for holding the outer edges of the bimetallic diaphragm, binding posts for the circuit to be closed, fixed contact strips connected to the binding posts, contacts connected with the outer part of the diaphragm thrown by reversal of the convexity of the diaphragm and adapted to close the switch circuit through the contact strips, contact arms and bimetallic diaphragm, a heater coil shunted across the circuit, an electrically conducting mount for the coil through which mount part of the heater coil current passes and a plunger capable of throwing the diaphragm.

10. A switch mechanism comprising a grounded casing, insulation forming a switch chamber within the casing, binding posts and corresponding contacts for a switch circuit, a clicker switch diaphragm, forming a part of a thermal pair, when heated opposing closing throw of the diaphragm and fastened between parts of the insulation within the casing, contact arms connected with the radially outer part of the diaphragm, movable contacts carried by the arms and adapted to engage the fixed contacts when the diaphragm is clicked, a spring tending to press the diaphragm toward open switch position, means for clicking the diaphragm against the pressure of the spring, a heater coil within the chamber shunted between the diaphragm and the ground in closed diaphragm position and an electrically

conducting spool upon which the heater coil is mounted and which limits the stroke of the diaphragm from open position to closed position.

11. A switch mechanism including a grounded casing, insulation forming a switch chamber within the casing, binding posts and corresponding fixed contacts for a switch circuit, a thermal pair in the form of a composite diaphragm including a clicker diaphragm fastened within the casing, arms connected with the outer part of the clicker diaphragm, movable contacts carried by the arms and adapted to engage the fixed contacts when the composite diaphragm is clicked, a spring tending to hold the composite diaphragm in open switch position, means for clicking the diaphragm against the pressure of the spring, an electrically conducting spool for a heater coil and a heater coil within the chamber shunted between the diaphragm and the ground through the coil and spool in closed switch position.

12. A switch mechanism including a grounded casing, insulation forming a switch chamber within the casing, binding posts and corresponding fixed contacts for a switch circuit, a thermal pair in the form of a composite diaphragm including a clicker diaphragm fastened within the casing, plunger means for throwing the diaphragm from normal open convex position to concave position, grounding means for the diaphragm, a spring tending normally to press the diaphragm into normal open position and insufficient in strength to reverse the diaphragm when the switch is closed, a spool within the chamber, a heating coil grounded through the casing at one end, connections between the other end of the heater coil and the diaphragm through the spool and means for altering the abutment against which the spring presses at the end farther from the diaphragm whereby the amount of heat required to be developed by the heater coil to reverse the diaphragm may be adjusted and the time of switch reversal may be changed.

13. A casing, insulation within the casing, a composite thermal pair clicker disc within the insulation, a plunger operating the disc, contact arms carried by the composite disc, fixed contacts engaged by the movable contacts to close a switch circuit through the disc, an electrically conducting spool within the casing, a heat coil mounted upon the spool, grounded at one end and connected to the spool at the other, thrown across the main circuit as a shunt when the switch is closed, connections from the spool to the composite disc and means for adjustably pressing the disc toward open position.

14. A thermally opened clicker time switch, comprising a casing, a plunger within the casing, a composite clicker disc including a thermally operated disc, held within the casing, a shunt resistance circuit, connections between the plunger and the composite disc, means having lost motion axially of the composite disc and limiting the throw of the disc, fixed contacts within the casing, arms carried by the disc closing against the contacts with throw of the disc to close the switch circuit, a spiral spring pressing the disc at one end of the spring to tend to open the switch, an abutment for the second end of the spring, and means for adjusting the position of the abutment to tighten or slacken the spiral spring.

15. A thermally operated time switch including a casing, a composite disc providing a thermal pair and embodying a clicker portion, contact arms carried by the disc, movable contacts on

the arms, insulation at the end and also near the circumference of the casing, holding the perimeter of the disc between them, fixed contacts within the casing engaged by the movable contacts, a plunger, insulation carried by the plunger, a bolt movable longitudinally within the insulation to give play to the composite disc, permitting it to jump beyond its center to close the contacts, a nut carried by the bolt resting against the composite disc on the side away from the plunger, a spiral spring pushing at one end to hold the disc in open switch position, an abutment for the other end of the spring, means for adjusting the abutment to tighten or slacken the spring, a spool about the spring and a heat coil about the spool electrically connected at one end through the spool to the composite disc and connected at the other end to the casing.

16. A switch mechanism including a grounded casing, insulation forming a switch chamber within the casing, binding posts and corresponding fixed contacts for a switch circuit, a thermal pair in the form of a composite diaphragm including a clicker diaphragm fastened within the casing, plunger means for throwing the diaphragm from normal open convex position to concave position, a spring tending normally to press the diaphragm into normal open position and insufficient in strength to reverse the diaphragm

when the switch is closed, a coil mount, a heating coil within the chamber grounded through the casing at one coil end, connections between the other end of the heater coil and the diaphragm passing through the coil mount and means for adjusting the strength of the spring, whereby the amount of thermal action required to reverse the diaphragm and open the switch may be adjusted.

17. In a time switch, a casing, disc insulation in the front of the casing, cylindrical insulation within the casing, a composite thermal pair clicker disc having contact arms, held at its perimeter between the front insulation and the cylindrical insulation, rear disc insulation, movable contacts operated by the clicker disc, a spool supported at one end within the rear insulation, a heater coil carried by the spool, connected at one end to the spool and at the other end to the casing, a spiral spring inside the spool normally pressing the composite disc toward open position, fixed contacts engaged by the movable contacts when the clicker disc is thrown, an abutment for the rear end of the spring adjustably mounted within the casing and connections between the spool and clicker switch through the spring.

ROBERT HETHERINGTON.
